UNITED STATES PATENT OFFICE.

ELMER E. WICKERSHAM, OF MARYSVILLE, CALIFORNIA, ASSIGNOR TO YUBA MANUFACTURING COMPANY, A CORPORATION OF CALIFORNIA.

CARBURETER.

1,243,666.

Specification of Letters Patent. Patented Oct. 16, 1917.

Application filed October 25, 1915. Serial No. 57,701.

To all whom it may concern:

Be it known that I, ELMER E. WICKERSHAM, a citizen of the United States, and a resident of Marysville, Yuba county, California, have invented a new and useful Carbureter, of which the following is a specification.

The invention relates to carbureters for internal combustion engines and particularly for internal combustion engines employing the heavier hydrocarbon fuels.

An object of the invention is to provide a carbureter in which there are positive connections between the throttle valve and the auxiliary air inlet valve, so that the two are simultaneously actuated.

Another object of the invention is to provide a carbureter in which all the incoming air is directed against a hot wall of the carbureting chamber, and by the design of the carbureter to provide means whereby the hot gases from the engine may be passed about the walls of said chamber.

Another object of the invention is to provide a carbureter in which the velocity of the mixture being drawn from the carbureting chamber is utilized without the intervention of moving parts to vary the pressure within the float chamber, so that the volume of fuel being discharged from the nozzle is varied in proportion to the speed of the engine.

Another object of the invention is to provide a carbureter capable of efficiently vaporizing kerosene, distillate or other heavy hydrocarbon fuels.

The invention possesses other advantageous features, which, with the foregoing, will be set forth at length in the following description, where I shall fully explain that preferred form of my invention which is illustrated in the drawings accompanying and forming part of the specification. The novelty of the invention will be included in the claims succeeding said description. From this it is apparent that I do not limit myself to the showing made by the said drawings and description, as I may adopt many variations within the scope of my invention as set forth in the said claims.

Referring to the drawings:

Figure 1 is a side elevation of an internal combustion engine with the carbureter of my invention applied thereto.

Fig. 2 is a vertical sectional view through the carbureter of my invention.

The carbureter of my invention comprises a carbureting chamber 2, arranged so that hot exhaust gases from the engine entering through the conduit 3 and emerging through the conduit 35 may circulate about in the chamber 4 and heat the bottom and side walls 5 and 6 of the carbureting chamber. Beneath the wall 7 which is also heated by the hot gases is a horizontal passage 8 communicating at one end with the spray nozzle 9 and at the other end with the fuel or float chamber 12. The temperature of fuel passing from the fuel chamber is thus raised before it reaches the nozzle and the subsequent spraying and vaporization of the fuel is promoted. This is of particular value where heavy hydrocarbon fuels are used.

In the fuel chamber 12, a float 13 actuating the valve 14 controls the admission of fuel into the fuel chamber from the supply pipe 34, a rising of the float shutting the valve and a lowering of the float opening it.

Leading into the carbureting chamber from the air inlet 15 is a by-pass 16 terminating in a tube 17 which incloses the upper end of the spray nozzle 9. This passage is always open and conducts the air past the downwardly directed discharge apertures 18 of the nozzle, drawing the fuel therefrom in a spray and impinging the mixture downwardly against the heated bottom wall of the chamber 2. The inlet 15 for the auxiliary air is controlled by the valve 19. The inner end of the inlet passage is curved downwardly, as at 21, and surrounds the tube 17, so that the air entering through the passage 21 is thoroughly mingled with the fuel mixture issuing from the tube 17 and is also directed upon the hot walls of the carbureting chamber. The fuel mixture is drawn out of the carbureting chamber through the outlet passage 22 which is controlled by the throttle valve 23. Positive mechanical connections are provided between the auxiliary air inlet valve 19 and the throttle valve 23. Levers 24 and 25 are secured to the stems of the throttle and air valves respectively and are connected by the link 26 which is made adjustable in the slotted portion of the air valve lever 25 by the thumb nut 27 so that the valves may be adjusted to suit the conditions. When the

100

105

points of connection of the link 26 to the levers 24 and 25 are equally spaced from the valve stems, the valves turn through the same angles, but as the effective length of the lever 25 is increased by means of the adjustable connection between the lever and the link, the angular movement of the valve 19 is less than the angular movement of the valve 23. The two valves then operate together simultaneously, the throttle valve controlling the speed of the engine and the air valve allowing the proper volume of air to pass into the carbureting chamber. A manually operated rod 37 attached to the lever 24 gives control of the movement of the two valves.

One of the objects of the present carbureter is to vary the pressure in the fuel chamber and hence the amount of fuel sprayed from the nozzle to correspond with the needs of the engine, and to accomplish this by the movement of the air as it is drawn out of the carbureting chamber. Curved outwardly and downwardly and opening directly into the path of the out-rushing fuel mixture in the passage 22 is a tube 28 connecting at the inner end with the duct 29, the tube and duct thus establishing communication between the carbureting chamber 2 and the fuel chamber 12 near its top. With the engine in operation and drawing the carbureted mixture out of the outlet passage 22, a certain quantity of the mixture is forced into the open end of the tube and through the duct 29 into the fuel chamber 12. At starting, the pressure in the fuel chamber is atmospheric, but with the advent of the mixture from the outlet passage driven through the duct, the pressure in the fuel chamber rises and hence the flow of fuel from the nozzle 9 is increased. As the velocity of the gases being drawn out of the carburetor past the intake of the tube 28 increases with higher engine speed, gas is driven with increasing violence through the duct, thus raising the pressure in the fuel chamber and forcing more fuel from the nozzle. The area of the duct 29 and hence the ratio of the pressures in the

fuel chamber and the carbureting chamber, is controlled by the valve 32 having a port or aperture 33 therethrough, the valve being rotatable to partially close the aperture so that the passing of gas through the tube 28 and the duct 29 may be restricted to correspond with given conditions of altitude or temperature.

It is, therefore, apparent that the pressure in the float chamber is maintained in such relation to the pressure in the carbureting chamber as to vary the quantity of fuel sprayed from the nozzle in accordance with the consumption of fuel in the engine.

I claim:

1. In a carburetor, a carbureting chamber, a fuel nozzle projecting into said carbureting chamber on one side, a main air inlet pipe projecting into said carbureting chamber from the opposite side and surrounding the said nozzle, an auxiliary valve-controlled air inlet passage in said chamber surrounding said main inlet pipe, a valve-controlled outlet passage in said chamber, and means adjustably connecting the valves in said outlet and inlet passages.

2. In a carburetor, a carbureting chamber, a fuel chamber having a fuel passage underlying said carbureting chamber, means for circulating hot exhaust gases between said carbureting chamber and said fuel passage, a valve controlled outlet in said carbureting chamber, an air inlet in said carbureting chamber comprising an open main passage and a valve controlled auxiliary passage surrounding said main passage, a fuel nozzle connected with said fuel passage projecting into said main inlet passage and means adjustably connecting the valves in said outlet and auxiliary inlet.

In testimony whereof, I have hereunto set my hand at San Francisco, California, this 11th day of October 1913.

ELMER E. WICKERSHAM.

In presence of--

M. T. Shinnay,

R. H. Barrows.
